United States Patent

Des. 236,795
Patented Sept. 16, 1975

236,795

DOOR KNOCKER OR THE LIKE

Rudolph Paulich, Mercer Island, Wash., assignor to
Columbia Specialty Co., Inc., Seattle, Wash.

Filed May 3, 1974, Ser. No. 466,612

Term of patent 14 years

Int. Cl. D10—06

U.S. Cl. D8—177

Fig. 2.

Fig. 1.

Fig. 3.

FIG. 1 is a front perspective view of a door knocker or the like showing my new design;

FIG. 2 is a left side elevational view thereof; and

FIG. 3 is a sectional elevational view taken along line 3—3 in FIG. 1.

The name is shown in broken lines for illustrative purposes only.

I claim:

The ornamental design for a door knocker or the like, as shown and described.
